UNITED STATES PATENT OFFICE.

JAMES B. RATHER, OF BROOKLYN, NEW YORK, ASSIGNOR TO CHARLES J. TAGLIABUE MANUFACTURING CO., OF BROOKLYN, NEW YORK, A CORPORATION OF NEW YORK.

FLAME-MEASURING DEVICE.

Application filed August 18, 1922. Serial No. 582,657.

To all whom it may concern:

Be it known that I, JAMES B. RATHER, a citizen of the United States of America, and a resident of the borough of Brooklyn, county 5 of Kings, city and State of New York, have invented certain new and useful Improvements in Flame-Measuring Devices, of which the following is a specification.

My invention relates to flame-measuring 10 devices, and has for its object to provide a simple and novel device whereby the dimensions of the flames of kerosene lamps, both as to breadth and height, may be measured in an efficient and reliable manner and with 15 a minimum of effort. Other objects of my invention will appear from the description hereinafter and the features of novelty will be pointed out in the appended claims.

In the accompanying drawings, which 20 illustrate an example of my invention without defining its limits, Figure 1 is a front elevation of the flame-measuring device; Fig. 2 is a side elevation thereof; Fig. 3 is a plan view, and Fig. 4 is a diagrammatic 25 view illustrating the type of flame for which the device is particularly adapted.

In its illustrated form, the device comprises members 5 and 6 arranged in pairs and each provided with slots 7 extending 30 lengthwise thereof, as shown in Fig. 1; the members 5 and 6 of each pair are arranged in spaced relation to and in registry with each other, as shown in Fig. 3, and are mounted upon carriages 8 adjustable length- 35 wise in the grooves 9 of a support 9^a. The latter is provided with fixed bearings 10, in which adjusting screws 10^a are rotatably mounted in a manner to prevent lengthwise movement relatively to the bearings 10.

40 The adjusting screws 10^a are in screw-threaded engagement with lugs 8^a forming part of or secured to the carriages 8, and are preferably provided with manipulating heads 10^b. A member 11, upon which a 45 scale 11^a is produced, is fixed upon one of the members of one of the pairs and extends movably across the face of one of the other pair of members; in the illustrated example, the member 11 is carried by one of the 50 members 5, preferably at the upper end thereof, and extends movably across the face of the co-operating member 6 of the other pair. The grooved support 9^a is hinged at 12 upon a support 13 which, as shown, may

be in the form of an upright stand mounted 55 upon a base 14 and having a horizontal member 15 upon which the grooved support 9^a is arranged to rest when the parts are in position illustrated in Fig. 1. In the preferred arrangement the support 9^a is provided 60 with an auxiliary scale 9^b for the purpose to be more fully set forth hereinafter. The members 5 and 6 constitute measuring 65 elements adjustable relatively to each other to measure distances as will appear more fully from the description hereinafter.

In practice, assuming that it is desired to first measure the width of a flame, the parts of the apparatus will occupy the positions shown in the drawings. In such case, a lamp 70 is placed in front of the device and a sight is taken through the slots 7 of the members 5 and the latter are shifted or adjusted by means of the adjusting screw 10^a and head 10^b until said slots register with each other 75 and with the one edge of the flame to be measured. A sight is then similarly taken through the slots of the members 6 and the latter are adjusted by means of the adjusting screw 10^a and its head 10^b until said 80 slots 7 align with each other and with the other edge of the flame. A reading is then taken from the scale 11^a, which indicates in predetermined units of measurement the width of said flame; it will be understood 85 that the scale 11^a begins at the right-hand edge of the member 5 in Fig. 1 and that the scale is read in connection with the right-hand edge of the member 6 in said figure.

To now measure the height of the flame, 90 the support 9^a is swung upon the hinge 12 to an upright position and into surface engagement with the upright member 13 of the stand or support, so that the members 5 and 6 now project in horizontal directions. 95 A sight is then taken through the slots 7 of the members 5 and the latter are adjusted in the manner previously described until said slots 7 register with each other and with the base of the flame. If the base of the 100 flame is below the level of the flame spreader on the lamp burner used in the test and this burner is of the type known as a hinged burner, the reading may be taken before the lamp is ignited and the position of the members 5 with reference to the top of the wick guide or holder of the burner noted 105 on the auxiliary scale 9^b. Then at any time

2 during the conduct of the test the slots 7 of the members 5 may be brought into alignment with the base of the flame by adjusting said members 5 to the previously ascertained position with reference to the auxiliary scale 9^b without disturbing the lamp. In any event, the members 6 are then similarly sighted and adjusted to bring the slots 7 thereof into registry with each other and with the upper edge of the flame being measured. The position of the one member 6 on the scale 11^a will, in this case, indicate in the predetermined units of measurement the height of said flame.

15 The dimensions of a flame, both as to breadth and height, are thus easily measured by simply swinging the support 9^a into horizontal and vertical positions, respectively, and then adjusting the members 5 and 6 to bring the slots 7 thereof into registry with each other and with the predetermined parts of the flame in the manner previously described.

16 The instrument or device is intended primarily for use in connection with oil tests, and more particularly in tests for kerosene oil which is used, to a large extent, in household lamps, railway signal lamps and the like. Up to the present time the most satisfactory flame measurements have been procured with the aid of a measuring device known as a photometer, whereby the flame is compared with a standardized source of light, and which requires the use of complicated and expensive apparatus and equipment including, for instance, a dark room for conducting the test. The present device overcomes the necessity for such complicated apparatus and equipment and makes it possible to positively and accurately adjust flames to predetermined dimensions and thereby secures an absolute uniformity in the candle-power development.

17 The device is simple in construction and is easily operated without the necessity for any particular skill, and may be utilized in a variety of different ways.

18 Various modifications may be made within the scope of the claims without departing from the nature of my invention.

19 I claim:

20 1. A device for measuring flames comprising a support, means adjustably mounted thereon and measuring elements movable relatively to each other on said means for measuring the width of a flame in one adjustment of said means and the height of a flame in another adjustment thereof.

21 2. A measuring device comprising a stand, a support pivotally mounted thereon and adjustable to horizontal and vertical positions, and measuring elements adjustably carried by said support and movable relatively to each other for measuring horizontal distances between given points in the

horizontal position of said support and vertical distances between given points in a vertical position thereof.

3. A measuring device comprising a stand, a support pivotally mounted thereon and adjustable to horizontal and vertical positions, slotted members arranged in cooperating pairs on said support for measuring respectively horizontal and vertical distances between given points as the support occupies either a horizontal or a vertical position, means whereby one pair of members is adjusted relatively to the other pair of members, there being means for indicating the distance between said pairs of members.

4. A measuring device comprising a stand, including an upright arm and a horizontal arm, a grooved support pivotally mounted upon said stand and arranged to rest against said horizontal arm in a horizontal position and against said upright arm in a vertical position, two carriages slidably mounted in the grooves of said support, a pair of slotted members mounted upon each carriage in spaced registry with each other, and adjusting screws whereby said carriages may be shifted relatively to said support to adjust the pairs of members relatively to each other.

5. A measuring device comprising a stand, including an upright arm and a horizontal arm, a grooved support pivotally mounted upon said stand and arranged to rest against said horizontal arm in a horizontal position and against said upright arm in a vertical position, two carriages slidably mounted in the grooves of said support, a pair of slotted members mounted upon each carriage in spaced registry with each other, adjusting screws whereby said carriages may be shifted relatively to said support to adjust the pairs of members relatively to each other, and a scale member carried by one member of one pair and extending across one member of the other pair and being provided with a scale to indicate the distance between the pairs of members.

6. A measuring device comprising a stand, a support pivotally mounted thereon and adjustable to horizontal and vertical positions, slotted members arranged in cooperating pairs on said support for measuring respectively horizontal and vertical distances between given points as the support occupies either a horizontal or a vertical position, means whereby one pair of members is adjusted relatively to the other pair of members, a scale member provided with a scale for indicating the distance between said pairs of members, there being an auxiliary scale for indicating the setting position of one of said members.

7. A measuring device comprising a stand, including an upright arm and a hori-

zontal arm, a grooved support pivotally mounted upon said stand and arranged to rest against said horizontal arm in a horizontal position and against said upright arm in a vertical position, two carriages slidably mounted in the grooves of said support, a pair of slotted members mounted upon each carriage in spaced registry with each other, adjusting screws whereby said carriages may be shifted relatively to said support to adjust the pairs of members

relatively to each other, a scale member carried by one member of one pair and extending across one member of the other pair and provided with a scale to indicate the 16 distance between the pairs of members, there being an auxiliary scale upon said grooved support for indicating the setting position of one pair of said members.

In testimony whereof I have hereunto set 20 my hand.

JAMES B. RATHER.
